Patented Aug. 7, 1917.

UNITED STATES PATENT OFFICE.

JOSEPH M. McGRATH AND JOHN T. LANE, OF SAN FRANCISCO, CALIFORNIA.

WINDOW-SCREEN.

1,236,193.

Specification of Letters Patent.

Patented Aug. 7, 1917.

Application filed May 31, 1916. Serial No. 100,889.

To all whom it may concern:

Be it known that we, JOSEPH M. McGRATH and JOHN T. LANE, citizens of the United States, residing at San Francisco, in the county of San Francisco and State of California, have invented new and useful Improvements in Window-Screens, of which the following is a specification.

The object of the present invention is to 10 provide a window screen which will provide perfect ventilation, which can be readily adjustable as to length, which can be used in all weathers, and with which the curtains will be protected from being soiled by parts 15 of the window screen exposed to dust or rain.

In the accompanying drawing, Figure 1 is a vertical section of a window equipped with our improved window screen; Fig. 2 is a broken top plan view thereof on an enlarged 20 scale; Fig. 3 is a broken horizontal section thereof on the line 3—3 of Fig. 6; Fig. 4 is an end view; Figs. 5 and 6 are cross sections on the lines 5—5 and 6—6 of Fig. 3.

On referring to the drawing, it will be 25 seen that our improved window screen consists of two sections, an inner window screen section 1 and an outer window screen section 2. Each section comprises an end piece 3, which, for a short distance from the bottom, has two parallel vertical edges 4, 5, the rear edge 4 diverging upwardly from the front edge 5 at an angle of almost 30°, as shown at 6, to a level a little lower than the front edge 5, and the top edge having two 35 upwardly sloping portions 7, 8, meeting at an angle of about 120°. On each end piece are secured two narrow parallel cleats 9, 10, the width over all of the two cleats being substantially equal to the thickness of the 40 window sash, and the two cleats being spaced from each other to form a groove of sufficient width to conveniently receive the sash weight cord at that end of the window, and, when the window screen is used at the top 45 of the window, to receive the pulley for said sash weight cord. To the rear edge of each end is secured the outer end of a shield plate section 11 or 11', which, conforming to the bent shape of the edge 4 where it diverges 50 upwardly from parallelism with the front edge 5 of the end, is likewise formed with a longitudinally extending bend 12. To the front vertical edge 5 of each end is nailed a metallic binding 13 of the outer end of a 55 screen section 14 or 14', and there is also secured to said front vertical edge 5 and to the

upwardly sloping front portion 8 of the top edge of said end, an end of a cover plate section 16 or 16', said cover plate section being, of course, bent, as shown at 17, to conform to 60 the change from the vertical plane of the front edge 5 to the slightly upwardly inclined plane of the front portion 8 of the top edge.

Each screen section 14 or 14', rectangular 65 in form, is bound along all four edges by a metallic binding 18, and the two screen sections 14 or 14', together with the two cover plate sections 16, 16' telescope one within the other at the front of the screen, while the 70 two shield sections 11, 11' telescope one within the other at the rear of the screen. For this purpose, at the front of the screen, the top of the inner screen section 14 is secured within the bottom of the inner cover plate 75 section 16, while the top of the outer screen section 14' is secured on the outside of the top of the outer cover plate section 16'. Also, the lower edge of the lower binding of the outer screen section, the lower margin of 80 the outer cover plate section, the upper margin of the outer cover plate section, and the upper and lower margins of the outer shield section are formed with grooves 19, 21, 22, 23 respectively in which the corresponding 85 edges of the corresponding inner elements can slide.

The inner end of the outer window screen section 2 is free except for its engagement, as above described, with the inner window 90 screen section 1. But to the inner end of the inner window screen section 1 is nailed a stop plate 24, which resembles in general form the outer end of said inner window screen section, and to the inner terminal portion of the outer window screen section 2, on the cover plate section and lower screen section binding respectively, are secured stops 95 26, 27, against which, when the window screen is extended to its full extent, the stop 24 is adapted to abut, and thereby prevent 100 the screen sections being entirely separated, which would cause inconvenience in reassembling the same.

The window screen is placed in position 105 either between the bottom of the bottom sash and the bottom of the window, or between the top of the top sash and the top of the window. In the latter case the cleats at the end of the sash sections are arranged on 110 either side of the sash cord and the sash weight pulley. When placed at the bottom

of the window, the screen is placed on the outside and the shield extends upwardly inside. When placed at the top of the window, the screen is placed on the inside and the shield extends downwardly on the outside. It is not necessary for the person placing it in the top of the window to reach said top, but it can be placed upon the top of the upper sash when in its lowered position, and, when the sash is raised to the top, the window screen slides up in advance of it. It will be seen that the window screen is securely maintained in the top of the window not only by the pulley stiles but by the engagement with the sash weight cords and the sash weight pulleys.

By reason of its telescoping action it is adjustable in length to any size of window.

The above arrangement permits of perfect ventilation of a room, since it allows complete circulation of air, the cool fresh air entering through the lower window screen and the foul hot air escaping through the upper. By both window screens rain and insects are excluded.

Any moisture passing through the screen portion of the window screen is prevented from entering the room by the shield portion thereof and escapes under the lower edge of said screen portion. When used in the top of the window, in which the screen is on the inside and the shield portion on the outer side, it is evident that said shield portion prevents any water reaching the screen portion.

The cover plate is constructed to have the same slope as the lower edge of the lower sash, so that, when the window screen is placed in its lower position, the entrance of water over the top of the window screen between the lower sash and the window screen is effectually prevented.

An important feature of the window

screen is that the shield prevents the lower portion of the curtains from coming in contact with the screen portion and becoming wet if said screen portion is wet on account of rain, and soiled if it is dusty.

We claim:—

1. In a screen for a window having vertically slideable sashes, window screen sections comprising end pieces, each having diverging side edges, and wider at one end than at the other, screen sections, slidably engaging each other, and each secured at one end to the edge of a corresponding end piece, shield plate sections slidably engaging each other, and each secured at one end to the other edge of the corresponding end piece, and cover plate sections, slidably engaging each other, and each continuous with a screen section, and secured at one end to a portion only of the wider end of the corresponding end piece, and to the adjacent portion of said first named edge. 65

2. In a screen for a window having vertically slideable sashes, window screen sections comprising end pieces, each having diverging side edges, and wider at one end than at the other, screen sections, slidably engaging each other, and each secured at one end to the edge of a corresponding end piece, shield plate sections slidably engaging each other, and each secured at one end to the other edge of the corresponding end piece, and cover plate sections, slidably engaging each other, and each continuous with a screen section, and secured at one end to a portion only of the wider end of the corresponding end piece, and to the adjacent portion of 70 said first named edge, the screen sections being on opposite sides of the cover plate sections. 75

JOSEPH M. McGRATH.
JOHN T. LANE.
